Matthew C. LEAGREY

UNITED STATES PATENT OFFICE.

HENRY NEWMAN, OF NEW YORK, N. Y., ASSIGNOR TO NEWMAN & VOLK INCORPORATED, OF NEW YORK, N. Y., A CORPORATION OF NEW YORK.

CAP.

1,410,216.

Specification of Letters Patent. Patented Mar. 21, 1922.

Application filed December 10, 1921. Serial No. 521,351.

To all whom it may concern:

Be it known that I, HENRY NEWMAN, a citizen of the United States of America, residing at New York city, Kings County, 5 N. Y., have invented a new and useful Cap, of which the following is a specification.

This invention relates to a headgear commonly termed caps, and the main object is to provide an adjustable cap which may be 10 made economically and have the maximum degree of adjustability without detracting from the stylish appearance of the cap.

Another object is to provide a construction which may be readily adjusted, but 15 which will securely retain its shape in any size.

Another object is to avoid wrinkling the cloth when the cap is adjusted to a small size.

20 Another object is to provide a construction which while it has a wide range of adjustability also has the appearance of a high-class non-adjustable style of cap.

In its preferred form, the invention is 25 carried into effect by providing the lower edges of the front and rear portions of the cap with inner and outer pairs of overlapping flaps or insertions. The outer pairs may be conveniently made of the same material as the body of the cap, and the inner flaps may be made of the same material as the lining, or they may constitute an extensible sweat-band. The outer front flaps are 30 preferably slidably connected over the peak 35 or visor and partially covered by the roll of the cap at the front.

Figure 1 is a side view of a cap embodying the improvements of the invention, and showing in dotted lines the top or body of 40 the cap distended.

Fig. 2 is a front view of the same.

Fig. 3 is a fragmentary sectional view on the plane of the line 3—3 of Fig. 1.

Fig. 4 is a fragmentary inside view.

45 Fig. 5 is a fragmentary outside view of a modification.

The top or body of the cap 7 may be formed of one or more pieces of any suitable fabric such as cloth, and suitably shaped 50 to the desired style or design. In its preferred form the invention is applied to a type of cap having a peak or visor 8, and a suitable type of fastener such as a snap fastener 9 is provided to hold the front of the 55 cap down to the peak.

The portions 10 and 11 are gathered or connected together part way down the sides, and the lower edges of these portions are respectively provided with extension flaps 12 and 13 which overlap. The two sides of 60 the cap are similarly constructed, and the flaps 12 and 12' are preferably in the form of straps which overlap each other and extend around the upper edge of the visor, and are provided respectively with the loops 65 14 and 14' through which the companion straps slide. To increase the head size of the cap the fastener 9 is released and the strap portions 12 and 12' are extended by sliding them through the loops 14' and 14 70 respectively until the desired size is obtained. The flaps 13 and 13' on the inside may be suitably held in place, as will hereinafter be understood.

Preferably the cap is provided with a 75 lining of suitable material such as silk or cloth made up of one or more pieces, which lining serves to cover the inner flaps 13 and 13'. In this case, the main part of the lining is made up of a series of pieces 15 and 16 80 suitably stitched together. The lower edge of the lining which is secured to the edge of the body or top of the cap consists of the portions 17 and 18 which constitute a sweatband, the portion 17 preferably being of 85 leather or other suitable material. The portion 18 may be of the same material as the parts 15 and 16, but is preferably stiffened so as to constitute a flap adapted to be inserted behind the part 17. The part 18 is 90 stitched or otherwise connected to the lower edge of the part 15. The left-hand end of the insert or flap 18 is of course movable with respect to the part 17. The sweatband 17 is stitched or otherwise secured to the 95 lower edge of the part 16 and also to the inside front edge of the cap, but leaving an opening for the insertion of the end of the flap 18. Preferably a flexible gusset 19 is provided so as to permit the expansion and contraction of the lining. The front ends of the flap 18 may be suitably connected to the inner wall of the cap or to each other by light elastic tape such as 20 so as to keep the flaps 18 stretched and smooth. 100

105 In the form shown in Fig. 5, the flap 12^a is the front end of a band adapted to pass around the rear of the cap, and in this case the top 7^a is formed in one piece with a pleat 22 and a gather 23. It should be understood 110

that other variations and modifications may be made without departing from the scope of the accompanying claims.

I claim:

- 5 1. An extensible cap having straps secured to the rear portion at the sides and adjustably connected in front, and an extensible lining having front and rear sweatband portions, the front sweatband 10 portion terminating at the sides of the cap, the rear sweatband portions having stiffened flaps slideable between the ends of the front sweatband portion and the inside of the cap.
  - 15 2. An extensible cap comprising a body having front and rear portions connected together part way down the sides, extension flaps secured to the unconnected rear edges of the front portions and extending 20 rearwardly, straps connected to the sides outside said flaps and adjustably connected in the front, a front sweatband portion extending from one side around to the other, and a rear sweatband portion having its 25 ends slideable between the front sweatband and the inside of the cap, said flaps being slideable between the rear sweatband portion and the inside of the cap.
  - 30 3. An extensible cap body having overlapping flaps at one side formed of the same material as the body of the cap, and an extensible lining having overlapping sweatband flaps, the inner of the first-mentioned flaps being slideable between the inner wall 35 of the body of the cap and the outer sweatband flap.
  - 35 4. An extensible cap comprising a body having front and rear portions connected
- part way down the sides, extension straps connected to the front edges of the rear 40 portions and adjustably connected in the front, front and rear sweatband portions, and an elastic connection between the ends of the rear sweatband portion housed between the front portion of the sweatband 45 and the inside of the cap body.
5. An adjustable cap comprising a body having front and rear portions connected part way down the sides, extension flaps of the same material secured to the unconnected front and rear edges of said portions, the outer flaps extending around the front and being slidably connected to each other, and a rear sweatband member forming a housing for the inner flaps which are 50 freely slideable between said sweatband member and the inside of the lower edge of the cap body.
  - 55 6. An adjustable cap comprising a body having front and rear portions connected together part way down the sides, extension flaps of the same material secured to the unconnected front and rear edges of said portions, the flaps which are secured to the rear edges extending around the front 65 of the cap and being slidably connected together, and means for slidably housing the other flaps.
  7. An extensible cap comprising a body portion with side straps adjustably connected across the front, a lining having side gussets, and overlapping flaps secured to said lining at the opposite edges of said gussets.

HENRY NEWMAN.
